UNITED STATES PATENT OFFICE

GEORGE W. DORMAN, OF EVERETT, WASHINGTON

TRIMMER-SAW LIFT

Application filed September 15, 1928. Serial No. 306,126.

My invention relates to mechanical lifts for trimmer saws, and similar devices, in which a work-performing element is to be placed into and out of its working position.

5 As well known the gang of trimmer saws commonly used in saw mills, for trimming the lumber to standard lengths, are driven continuously but are normally out of working position, and one or more are selected by 10 an attendant and lowered to the work.

The principal object of my invention is to provide a mechanical, manually controlled trimmer saw lift, conveniently operated by the attendant to raise or lower the saw into 15 and out of working position, and the lifting and lowering mechanism then to become automatically disengaged, thereby to hold the saw lift in its assumed position until again manually operated by the attendant.

20 Another object of my invention is to provide a mechanical trimmer saw lift positive in action, relatively simple in construction, simple to operate and durable in service.

A further object of my invention is to provide 25 a trimmer saw lift, consisting of devices adapted and arranged to be enclosed in a housing adapted for holding a substantial volume of lubricant in which the operating parts run, and furthermore protecting the 30 operating parts from dust. Furthermore, such housing shall be made of such relatively narrow width that the individual units of the battery of saws may be placed as closely together as desirable.

35 I attain the said objects in a combination comprising a housing, a shaft journaled therein, a primary sprocket fixed on said shaft, an idler sprocket aligned with the first mentioned sprocket, a sprocket chain running on said sprockets, a lift-device including a rod connected at one end to said sprocket chain, a driving element normally connected to said shaft, and a manually operated control, whereby to disconnect said driving connection such control comprising devices arranged to disconnect automatically said driving connection from said shaft, and stop the rotation of the latter, at the end of each half-circuit travel of said sprocket chain.

50 While I have described my invention with

reference to its particular use in connection with trimmer saws, of course I do not restrict myself to such use, but the combinations included in my mechanism also serve as a combined clutch and stop mechanism useable for other devices than trimmer saws.

The mechanism combined in my mechanical lift, the features thereof, and its mode of operation are hereinafter fully described with reference to the accompanying drawings.

In the drawings:

Fig. 1 shows a diagrammatic side elevation of one unit of my trimmer saw lift mounted in place, and operating one of a gang of trimmer saws;

Fig. 2 shows a perspective exterior view of one of my trimmer saw lifts, and a part of the rod connecting the same to a trimmer saw;

Fig. 3 shows a perspective view similar to Fig. 2, except that the upper half of the housing has been removed to disclose the parts contained therein;

Fig. 4 shows in elevation a fragmentary larger scale detail of the sprockets and the sprocket-chain running thereon;

Fig. 5 shows in a fragmentary view the mechanism contained in the housing, a portion of the gear being broken away to disclose the devices covered thereby; this view of my mechanism being from the opposite side to that shown in Fig. 3;

Fig. 6 shows a fragmentary sectional view similar to Fig. 5 with the operating parts thrown into another position;

Fig. 7 shows a fragmentary sectional view similar to Fig. 6 illustrating further phases of operation;

Fig. 8 shows a longitudinal sectional view through the housing; also the gear normally loose on the drive shaft, part of the devices operable to connect the gear with the shaft, and the driven pinion driving the gear. This view is taken from the same side as Fig. 3;

Fig. 9 shows a transverse section on the line 9—9 of Fig. 8 showing only a portion of the casing, the driven gear and the shaft therefor;

Figs. 10 and 11 show in perspective dismounted parts of my mechanism;

Fig. 12 is a view similar to Fig. 5 illustrating another phase in the operation of my invention;

Fig. 13 shows a section taken on the line 13—13 of Fig. 12 looking in the direction indicated by the arrows;

Figs. 14 and 15 show a detail in side elevation and end elevation respectively, of what I term the "transmission element" of my mechanism;

Fig. 16 shows on a large scale a detail of said transmission element and cooperating devices;

Fig. 17 shows in end elevation the mechanism shown in Fig. 16;

Figs. 18, 19 and 20 show in perspective other dismounted parts of my mechanism;

Fig. 21 shows a section of the transmission element taken on the line 21—21 of Fig. 16, and shows further some of the parts carried by said transmission element but removed therefrom; and

Figs. 22 and 23 show respectively, in side elevation and top view details of what I term the primary stop-bar.

Referring first to Fig. 1; *a* represents one of a battery of trimmer saws, each keyed on a shaft as *b* carried by an arm, or lift device *e*, pivoted on a shaft *c*. The extremity of the arm *e* is connected to a rod *f* longitudinally adjustable with a rod 64, the upper end of which is connected to the mechanism provided by me for raising and lowering the arm *e*, and for automatically releasing it from the raising and lowering devices, when the saw is either in its up or its down position and then holding it in that position until my mechanism is again manually actuated for placing the saw in another position.

The saw *a* is driven continuously and is normally lifted from the saw table *d* as usual; the saw being raised and lowered from and to the work table by the manual control of my mechanism.

My invention comprises a housing 2 firmly mounted by suitable supports 3 above the saw as indicated in Figs. 1 and 2. The housing, for convenience, may be constructed in two sections, namely a base and a top part as shown by Figs. 2 and 3. A driving shaft 5 is journaled in the housing as at 5^a (Fig. 2), and on such shaft is keyed a pinion 7 meshing with a gear 8 rotatably mounted on a driven shaft 9 journaled in the housing. The gear 8 is provided with a lateral circumferential flange 10 on one side and such flange is provided with internal ratchet teeth 10^a and external gear teeth 10^b.

A sprocket 61 is secured on the shaft 9, exterior of the housing, and a similar idler sprocket 62 is mounted adjacent thereto on a stub shaft 66, provided on the exterior of the base portion of the housing 2. A sprocket

chain 63 is mounted over the said sprockets. The upper end of the rod 64 is pivotally connected to the said chain by a special link 63^a on a pin 64^a, and the lower end of the rod is connected to the saw as mentioned. To accommodate said arrangement each of the said sprockets have a portion cut away as at 61^a, 62^a. The chain and sprockets are so relatively proportioned that two rotations of the sprockets will cause one complete revolution or circuit of travel of the chain.

On the driving shaft 9 is fixed a transmission element 11, a detail which is shown by itself in side elevation and end elevation in

Figs. 14 and 15, respectively, and is further shown on a larger scale in Fig. 16 with the parts mounted on said transmission element

and operating therewith, and again in Fig. 21, which is a section on the line 21 of Fig. 16, showing said transmission element with some of its parts removed, but arranged for assembly on the transmission element. The transmission element 11 has a projection 12 (see Figures 14 and 15) and is provided with

bosses 13, 14 and 14^a, in which are pivoted certain operating parts and has a flat surface 15 on which slides a block 18 secured in place

by pins 18^a (see Figs. 16 and 21). A dog 17 is pivoted for rotation by a pin 13^a on the transmission element 11, as shown by Fig. 16.

A perspective detail of this dog is shown by Fig. 20. It comprises a toe 17^a and a head 17^b, with the head being adapted to bear on the projection 12 of the transmission element 11 and the toe 17^a adapted to bear against the

slidable block 18, as more clearly shown by Fig. 16.

On the boss 14^a of the transmission element 11 is pivoted a primary angular pawl 31 by a pivot pin 19. A detail of this dog is shown in Fig. 19. It consists of a sleeve portion 19^a integral with which is a toe 30 and spaced ears 32. There is further pivoted at 14 on the transmission element 11 a secondary pawl 31^a, the construction of which is similar to the primary pawl 31. The perforated ears

32 of said pawls have secured thereto a U-shaped expansion spring 33 by pins 33^a. The spring 33 when unrestrained, positions the

pawls 31 and 31^a as shown in Fig. 7, thus engaging the same with the internal ratchet teeth of the gear 8, in so doing the toes 30 of the pawls 31 and 31^a bear down on the sliding

block 18 and cause the same to rock the dog 17 into the position in which it is shown in Fig. 7. In the position of the parts last referred to the gear 8 is connected with the driven shaft 9.

In order to disconnect the transmission element 11 from the gear 8 and simultaneously hold the shaft 9 against further rotation I provide a stop mechanism consisting of a primary stop-bar 44, and a secondary stop-bar 40; these stop bars being pivoted to one

side wall of the housing as shown in Figs. 130

5 and 12. The free ends of the said stop bars are pivotally connected to a rocker arm 43. A detail of the primary stop bar 44 is shown by Figs. 22 and 23. It comprises a boss 44^a by which it is mounted on a pivot shaft 45 journaled in a wall of the housing 2. The free end of the stop bar 44 is provided with a slotted head 44^b; and rigidly fixed on the outer end of the shaft 45 is a cam arm 44^c. 10 A detail of the secondary stop bar 40 is shown by Fig. 11. The free end of the latter stop bar has a head 41 provided with a slot 42. A detail of the rocker arm 43 is shown by Fig. 10. It is mounted on a pivot pin 43^a provided in the adjacent wall of the housing. The slotted head of the primary stop bar 44 is connected to one end of a rocker arm by a pin 42^b and the slotted head of the secondary stop bar 40 is connected to 15 the rocker arm by the pin 42^a. The rocker arm is normally held in the position in which it is shown in Fig. 12 by a rod 51 on which is placed an expansion coil spring 52, the compression of which is adjusted by a nut 52^a. The rocker arm is operated by a bell-crank 54 to which is connected a cord 55 leading to a distant point as 60^a, in Fig. 1 where the attendant is stationed. The bell-crank is pivoted on an arm 2^b mounted on the 20 cover of the housing as at 2^a, and the bell crank is connected to the rocker arm 43 by a rod 53.

By the description of the parts of my mechanism, above given, its operations will be 35 readily understood. Initially my mechanism has been so manually operated as to position the sprocket chain 63, as shown in Fig. 2, in which position the rod 64, and its extension *f* to the lift-arm or device *e* has been raised 40 so as to lift the saw from the work table.

In Fig. 12, the transmission element 11 has become positioned to cause the dog 17 thereon to abut against the primary stop-bar 44, which abutment has caused said dog to move 45 the slideable link 18 against the toes 30 of said primary and secondary pawls 31, 31^a and thereby release the latter so as to retract them from the internal ratchet teeth of the gear 8; and since the transmission element 11 is 50 fast on the driven shaft 9 the latter is held against rotation by the abutment of the dog 17 with the primary stop bar 44. Hence the sprocket chain is held stationary for the time being. In order to change the position 55 of the saw, that is, bring it down to the work, the attendant pulls the bell-crank 54 clockwise as shown in Fig. 12, and thus rocks the rocker arm 43 counter-clockwise, in so doing lifting the primary stop arm 44 from the position in which it is shown, and hence releases the dog 17, which release permits the 60 spring 33 to act to throw the pawls into engagement with the internal ratchet teeth of the gear 8 thus connecting the latter with the driven shaft 9 through the medium of the

transmission mechanism. Since the shaft 9 is then driven by the pinion 7 through the gear 8, the sprocket 61 fast on said shaft will be rotated. The rocker arm 43 and the stop bars 44 and 40, have now been given a 70 position similar to that shown by Fig. 5, thus lifting the primary stop bar 44 to its inactive position, and lowering the secondary stop bar 40 to its active position, which causes it to arrest further movement of the transmission. 75 The saw has now been lowered to its work as mentioned.

In order to again lift the saw from the work table the attendant will release the bell-crank 54 so that spring 52 may function 80 to rock the bell crank counter clockwise into its initial position, bringing the rocker-arm 43, and the primary and secondary stop-bars back into the position in which they are shown in Fig. 12.

The dog 17 being thus released from its abutment with the secondary stop-bar 40, the transmission member 11 and therewith the shaft 9 may again rotate, but as evident from Fig. 12 the parts have now become so positioned that the primary stop-bar 44 would be in the path of motion of the dog 17. In order to permit the dog to pass, means must be provided to lift the primary stop-bar 44 at this instant. To this end the sprocket-chain is provided with a projecting link 70, in which is journaled a cam-roller 71, which is arranged to contact with the cam-arm 44^c, an integral part of the primary stop-bar 44 as above described, and thus by lifting said cam-arm also lifts the primary stop-bar 44 out of the way of the dog 17, so as to permit the further movement of the transmission mechanism and therewith the rotation of the shaft 9; and as soon as the cam-roller 17 has passed 105 from under the cam-arm 44^c the latter will, of course, drop and cause the primary stop-bar 44 to resume its position in Fig. 12, and thus again arrest the rotation of the transmission element and the shaft 9 when the 110 sprocket chain has completed another half circuit of its travel.

For this reason the sprocket 61 and the sprocket chain 63 are so relatively proportioned as before mentioned that one complete revolution of the said sprocket 61 will cause the sprocket chain to travel half its length; or, in other words make a half circuit of its travel.

It is to be noted that by my mechanism 120 the lifting and lowering of the trimmer saw from and to its work is not done by any sudden jerk, but by a uniform though relatively rapid motion. Furthermore, all moving parts except the chain and sprocket are 125 enclosed in a dust proof casing, the lower part of which may be kept filled with lubricant, and furthermore, the casing is relatively narrow, thus permitting the trimmer saws to be set closely together as desirable.

It is to be particularly noted that the combination presented by the above structure involves a continuously driven element and the provision of automatically operative, manually selective means by which this continuously driven element is positively connected to the saw lowering and lifting means, so that such lowering and lifting means is positively driven both for lowering the saw and 10 for raising it. Thus, the movement of the saw, both in the lowering and raising operation, is positively actuated, insuring a steady, even descent and raising movement of the saw, with the rapidity of such movement depending upon the speed of movement of the 15 continuously driven element and thus in no wise depending in any way upon the weight of the saw and its mounting and insuring that the operator may positively control both lowering and raising movements to insure that the lower or operative plane of the saw will, subject to the initial manual adjustment of the connection of the lifting rod, always be the same operative plane without the possibility of variation and without the liability of 20 error. Furthermore, it will be noted that the continuously driven element makes substantially a complete revolution in each lowering movement of the saw and a complete 25 revolution in each raising movement of the saw. This provides for a simplification of the control of the movement in that in each lowering and raising movement, the connection with the continuously driven element 30 is interrupted at substantially the same point.

I claim:

1. In a saw lift and the like, the combination of, a revolute shaft, a primary sprocket fixed on said shaft, an idler sprocket alined with the first mentioned sprocket, a sprocket chain running on said sprockets the diameter of each of said sprocket wheels and the length of the sprocket chain being proportioned to move the chain half its path of 40 travel upon one complete revolution of the sprocket wheels, a lift device including a rod connected at one end to said sprocket chain, a gear loose on said shaft, a driven pinion in mesh with said gear, a transmission element fixed on said shaft and including spring-controlled means normally engaged with said gear to positively operate the chain throughout a full revolution of the gear, a stop mechanism carried by said transmission element, 45 said stop mechanism operable to render said gear-engaging means inactive and manually controlled devices arranged to engage and hold said stop mechanism and simultaneously to operate the same to release said gear at the end of each half-circuit travel of said sprocket chain.

2. In a saw lift and the like, the combination of, a revolute shaft, a primary sprocket fixed on said shaft, an idler sprocket

alined with the first mentioned sprocket, a sprocket chain running on said sprockets the diameter of each of said sprocket wheels and the length of the sprocket chain being proportioned to move the chain half its path of 50 travel upon one complete revolution of the sprocket wheels, a lift device including a rod connected at one end to said sprocket chain, a gear loose on said shaft, a driven pinion in mesh with said gear, a transmission element fixed on said shaft and including spring-controlled means normally engaged with said gear throughout one complete revolution of the gear, a stop mechanism carried by said transmission element, said stop mechanism operable to render said gear-engaging means 55 inactive and manually controlled devices including a spring-controlled rocker-arm, stop-bars pivoted adjacent the extremities of said rocker-arm and connected therewith, and cooperating means provided on the sprocket-chain and on one of said stop-bars adapted to lift the latter into inactive position in one position of said transmission element.

3. In a saw lift and the like, the combination of, a housing, a shaft journaled in said housing, a primary sprocket fixed on said shaft, exterior of the housing, an idler sprocket carried by the housing and alined with the first mentioned sprocket, a sprocket chain running on said sprockets, the diameter of each of said sprocket wheels and the length of the sprocket chain being proportioned to move the chain half its path of 60 travel upon one complete revolution of the sprocket wheels, a lift device including a rod connected at one end to said sprocket chain, a gear loose on said shaft within the housing, a driven pinion journaled in said housing in mesh with said gear, a transmission element fixed on said shaft and including spring-controlled pawls normally engaged with said gear, a stop mechanism carried by said transmission element, said stop mechanism operable to render said gear-engaging pawls inactive following each complete revolution of the gear, and manually controlled devices arranged to engage and hold said stop mechanism and simultaneously to operate the same to release said gear at the end of each half-circuit travel of said sprocket chain.

4. In a saw lift and the like, the combination of, a housing, a shaft journaled in said housing, a primary sprocket fixed on said shaft exterior of the housing, an idler sprocket carried by the housing and alined with the first mentioned sprocket, a sprocket chain running on said sprockets, the diameter of each of said sprocket wheels and the length of the sprocket chain being proportioned to move the chain half its path of 65 travel upon one complete revolution of the sprocket wheels, a lift device including a rod connected at one end to said sprocket chain, a gear

loose on said shaft within the housing, a driven pinion journaled in said housing in mesh with said gear, a transmission element fixed on said shaft and including spring-controlled 5 pawls normally engaged with said gear, a stop mechanism carried by said transmission element, said stop mechanism operable to render said gear-engaging pawls inactive following each complete revolution of the 10 gear, and manually controlled device including a spring-controlled rocker-arm, stop-bars pivoted adjacent the extremities of said rocker-arm and connected therewith, and co-operating means provided on the sprocket- 15 chain and on one of said stop-bars adapted to lift the latter into inactive position in one position of said transmission element.

5. In a saw lift and the like, the combination of, a housing, a shaft journaled in said 20 housing, a primary sprocket fixed on said shaft, an idler sprocket carried by the housing in alinement with the first mentioned sprocket, the diameter of each of said sprocket wheels and the length of the sprocket chain 25 being proportioned to move the chain half its path of travel upon one complete revolution of the sprocket wheels, a sprocket chain running on said sprockets, a lift device including a rod connected at one end to said 30 sprocket chain, a gear loose on said shaft within the housing, said gear provided with a peripheral flange and said flange provided with internal ratchet teeth, a driven pinion journaled in said housing in mesh with said 35 gear, a transmission element fixed on said shaft within said flange of the said gear, primary and secondary angular spring controlled pawls included in said transmission element and normally engaged with the said 40 internal ratchet teeth of said gear, a spring controlled rocker-arm pivoted in said housing, manual means for tilting such rocker-arm, primary and secondary stop-bars pivoted, respectively, adjacent the extremities of 45 said rocker-arm and connected therewith, a 50 slideable block arranged to bear against one leg of said pawls respectively and a dog pivoted on said transmission element bearing against said slideable block and adapted to abut with 55 said stop-bars, thereby to be operated to move 60 said block into position for retracting said pawls and cooperating devices provided on the sprocket chain and on one of said stop-bars 65 adapted to lift the latter into inactive position of said transmission element.

6. In a saw lift and the like, the combination of, a housing, a shaft journaled in said 70 housing, a primary sprocket fixed on said shaft, an idler sprocket carried by the housing in alinement with the first mentioned sprocket, the diameter of each of said sprocket 75 wheels and the length of the sprocket chain being proportioned to move the chain half its path of travel upon one complete revolution of the sprocket wheels, a sprocket chain running on said sprockets, a lift device including a rod connected at one end to said 80 sprocket chain, a gear loose on said shaft within the housing, said gear provided with a peripheral flange and said flange provided with internal ratchet teeth, a driven pinion journaled in said housing in mesh with said gear, a transmission element fixed on said shaft within said flange of the said gear, primary and secondary angular spring controlled pawls included in said transmission element and normally engaged with the said internal ratchet teeth of said gear, a spring controlled rocker-arm pivoted in said housing, manual means for tilting such rocker-arm, primary and secondary stop-bars pivoted, respectively, adjacent the extremities of said rocker-arm and connected therewith, a slideable block arranged to bear against one leg of said pawls respectively, a dog pivoted on said transmission element bearing against said slideable block and adapted to abut with said stop-bars, thereby to be operated to move said block into position for retracting said pawls and cooperating devices provided on the sprocket chain and on one of said stop-bars adapted to lift the latter into inactive position of said transmission element.

7. The combination with a trimmer saw mounted for movement into and out of an operative plane, of means for moving the saw into and out of said operative plane, said means including a continuously and positively driven element, a member mounted for travel in an endless path, a connection between said member and the saw, and automatically operative manually controlled means for connecting said member to the positively driven element for actuating the member positively throughout its full path of movement, said means adapted to automatically interrupt the positive connection between the member and said element at those predetermined and successive intervals in the movement of the member which determines the operative plane of the saw.

8. The combination with a trimmer saw mounted for movement into an operative and inoperative plane, of means for moving the saw into and out of said plane, said means including a continuously driven element, a member mounted for travel in an endless path, a connection between said member and the saw, means for positively connecting said member to the continuously driven element adapted to cause the movement of said member in response to the movement of the element, automatically operative stops adapted following each successive complete revolution of the element to disconnect the member from the element when the member has moved through substantially one-half of its path of travel, and manual means for controlling the automatically operable stops.

9. The combination with a trimmer saw mounted for movement into and out of an operative plane, of means for moving the saw, said

within the housing, said gear provided with a peripheral flange and said flange provided with internal ratchet teeth, a driven pinion journaled in said housing in mesh with said gear, a transmission element fixed on said shaft within said flange of the said gear, primary and secondary angular spring controlled pawls included in said transmission element and normally engaged with the said internal ratchet teeth of said gear, a spring controlled rocker-arm pivoted in said housing, manual means for tilting such rocker-arm, primary and secondary stop-bars pivoted, respectively, adjacent the extremities of said rocker-arm and connected therewith, a slideable block arranged to bear against one leg of said pawls respectively, a dog pivoted on said transmission element bearing against said slideable block and adapted to abut with said stop-bars, thereby to be operated to move said block into position for retracting said pawls and cooperating devices provided on the sprocket chain and on one of said stop-bars adapted to lift the latter into inactive position of said transmission element.

10. The combination with a trimmer saw mounted for movement into and out of an operative plane, of means for moving the saw into and out of said operative plane, said means including a continuously and positively driven element, a member mounted for travel in an endless path, a connection between said member and the saw, and automatically operative manually controlled means for connecting said member to the positively driven element for actuating the member positively throughout its full path of movement, said means adapted to automatically interrupt the positive connection between the member and said element at those predetermined and successive intervals in the movement of the member which determines the operative plane of the saw.

11. The combination with a trimmer saw mounted for movement into an operative and inoperative plane, of means for moving the saw into and out of said plane, said means including a continuously driven element, a member mounted for travel in an endless path, a connection between said member and the saw, means for positively connecting said member to the continuously driven element adapted to cause the movement of said member in response to the movement of the element, automatically operative stops adapted following each successive complete revolution of the element to disconnect the member from the element when the member has moved through substantially one-half of its path of travel, and manual means for controlling the automatically operable stops.

12. The combination with a trimmer saw mounted for movement into and out of an operative plane, of means for moving the saw, said

means including a continuously driven element formed with a ratchet, a member mounted to travel in an endless path, a connection between said member and the saw, pawls adapted automatically to engage said ratchet to connect the member and the element for positive actuation of the member, stops adapted automatically to disengage said pawls from said ratchet following each complete revolution of the element thereby to interrupt the movement of the member, and means for manually controlling the stops, the relation of the continuously driven element and said member being such that two revolutions of the element are necessary to compel one complete movement of the member.

10. The combination with a trimmer saw mounted for bodily movement into and out of an operative plane, of means for moving the saw, said means including a positively and continuously driven element formed with a ratchet, a member mounted for travel in an endless path, a connection between said member and the saw, pawls carried by said member, said pawls automatically operated to interconnect said member and the ratchet to thereby positively drive the member, means operative to disconnect the pawls from the ratchet to thereby free the member from said continuously driven element, a stop arranged in the path of movement of the disconnecting means to operate the latter, to disconnect the pawls from the ratchet, a second stop in the path of movement of the disconnecting means also to interrupt the movement of the disconnecting means and thereby automatically disconnect the pawls and ratchet, and manually operable means whereby the positions of the stops with respect to the path of movement of the disconnecting means may be determined, the relation of the member and element being such that approximately two revolutions of the element are necessary to compel a complete movement of the member.

45. 11. Automatic manually operative mechanism for lowering and raising a trimmer saw into and out of operative position, including a continuously driven gear formed with a ratchet, an endless chain supported for movement in a fixed path, means carried by the chain for connecting the saw to the chain, a member moving with the chain, pawls carried by said member, means adapted automatically to operate the pawls to engage the ratchet and thus cause a positive movement of the chain with said gear, a disconnecting element carried by said member and operated to release the pawls from the ratchet, a stop arranged in the path of movement of the disconnecting element to operate the latter and thereby disconnect the chain from the gear, a second stop in the path of the disconnecting element to operate the latter to disconnect the pawls from the ratchet and thereby disconnect the chain from the gear,

and manually operative means for positioning said stops, the relation of the gear and chain being such that at least two revolutions of the gear are necessary to move the chain through one complete circuit, cooperative means provided on the chain and one of said stops adapted to move the latter into inactive position during one phase of action of said member.

12. An automatic manually operative means for lowering and raising a trimmer saw relative to an operative saw plane, including a continuously driven gear formed with a ratchet, spaced pinions, one of which is arranged coaxial with the gear, an endless chain carried by said pinions, a member movable with one of the pinions, pawls carried by the member, means for automatically actuating the pawls to engage the same with the ratchet for connecting the chain and gear to cause positive movement of the chain by the gear, means connecting the chain to the saw, means carried by the member and operative to disengage the pawls from the ratchet and disconnect the chain from the gear, a stop normally interposed in the path of movement of the disconnecting means and operative to cause the disengagement of the pawls from the ratchet, manual means for controlling the position of said stop, and a second stop adapted to be automatically interposed in the path of movement of the disconnecting means to disengage the pawls from the ratchet, the second stop being automatically positioned in the manual control of the first mentioned stop, the relation of the chain and gear being such that each complete rotation of the gear causes a movement of the chain substantially equal to one-half its complete circuit of travel, cooperative means provided on the chain and one of said stops adapted to move the latter into inactive position during one phase of action of said member.

GEORGE W. DORMAN.
